UNITED STATES PATENT OFFICE.

HARRY P. MACDONALD, OF MONTCLAIR, NEW JERSEY, ASSIGNOR TO THE SNEAD & CO.
IRON WORKS, OF JERSEY CITY, NEW JERSEY, A CORPORATION OF NEW JERSEY.

PATTERN-DRAWING APPARATUS.

1,088,084.

Specification of Letters Patent.

Patented Feb. 24, 1914.

Application filed June 28, 1913. Serial No. 776,303.

To all whom it may concern:

Be it known that I, HARRY P. MACDONALD, a citizen of the United States, residing at Montclair, in the county of Essex and State 5 of New Jersey, have invented certain new and useful Improvements in Pattern-Drawing Apparatus, of which the following is a specification.

This invention relates to sand molding apparatus, and has reference particularly to an improved form of pattern drawing mechanism which is simple and inexpensive in construction, and effective in operation.

My invention further contemplates the 15 provision of improved means for supporting the pattern table during the ramming of the mold; and the provision of an improved arrangement of operating mechanism for raising and lowering the pattern table.

20 Other objects of the invention reside in the provision of improved means for preventing sand, dust and dirt from having access to the operating mechanism, and of improved means for lubricating the operating mechanism.

25 The foregoing, together with such other objects as may hereinafter appear or are incident to the invention, I attain by means of a structure which I have illustrated in 30 preferred form in the accompanying drawings, wherein—

Figure 1 is a plan view of my improved apparatus with the pattern table removed; Fig. 2 is an irregular section on the line 35 II—II of Fig. 1; Fig. 3 is a section through one of the operating shafts and illustrates the method of lubricating the parts; Fig. 4 is a plan view of a detail of my invention; and Figure 5 is an end elevation of a detail 40 of my invention.

Referring now to the drawings, it will be seen that my apparatus comprises a main frame 7 preferably made of cast iron, which frame is open at the ends and provided with 45 side walls 8 which extend upwardly. The ends of the frame are partially closed by means of the cast end pieces 9 which extend between the side walls. The pattern table 10 fits snugly between the side walls of the 50 frame and can be readily raised and lowered, the operating mechanism for raising and lowering the table being of the toggle type, as will further appear. Secured to each end of the pattern table is a down- 55 wardly depending end plate 11, said plates

abutting against the exterior faces of the end pieces 9 of the frame work. It will be seen from the foregoing that the framework and the pattern table together with the end plates 11 constitute an inclosed box in which 60 the operating mechanism is mounted. The operating mechanism comprises the toggles 12 which are arranged in pairs at opposite ends of the apparatus; the segmental gears 13 which are likewise arranged in pairs adjacent the central portion of the apparatus; the links 14 which connect the gears and the toggles; the rock shafts 15 and 16 to which the gears 13 are keyed; and the operating lever 17 keyed to the rock shaft 15. The 65 rock shafts 15 and 16 have bearings in the side walls and in a saddle plate or bearing 18 carried on the block 19 which is secured to the central portion of the main frame 7. The pattern table is adjustably carried on 70 the toggles 12 by means of the adjustable connections 20 which are of the type illustrated in my co-pending application Ser. No. 738,694, filed Dec. 26, 1912. It will be clear from inspection of Fig. 2 that the pairs of 75 segmental gears intermesh, and as they are rotated, the links 14 will be either drawn inwardly or moved outwardly, depending upon the direction in which the hand lever 17 is turned, this movement of the links 80 causing the toggles to raise or lower the pattern table, 10, as the case may be. In order to automatically lock the toggles in raised 85 position, the apparatus is so arranged that the toggles are moved slightly past center 90 and take against the set screws 21 which are threaded into the end pieces 9, said set screws preventing further outward movement of the toggles. The pattern table is guided during the raising and lowering movement by 95 means of the guide rods or posts 22 which slide in apertures 23 in the end pieces 9, the said guide posts having a ball and socket mounting 24 in the pattern table. The guide posts are of the same construction and serve 100 the same purposes as those described in my co-pending application above set forth. In order to relieve the operating mechanism of a portion of the weight of the pattern table and to maintain the load pressure of the pattern table on the operating mechanism at a more uniform degree, I provide a plurality of counterbalance compression springs 25, said springs being mounted in the cylinders 105 26 carried by the frame 7. The pattern table 110

26 carried by the frame 7. The pattern table 110

is provided with a plurality of downwardly depending posts 27 which telescope within the springs 25 and project within the cylinders 26. By this arrangement, buckling of the springs 25 is prevented. The springs are of such weight and length that they are under compression at all times, the degree of compression of course varying according to the elevation of the pattern table.

10 It will be clear that the mechanism for raising and lowering the table is simple in character and effective in operation. The fact that the segmental gears are also in effect rock arms simplifies the mechanism. 15 The arrangement avoids torsion on the shafts.

Referring now to the box-like arrangement of the frame work and the pattern table, it will be seen that the operating mechanism is entirely inclosed and is protected from sand, dirt and dust which might work past the pattern table. Directing attention particularly to the end plates 11, it will be observed that I have provided a port 28 in each of said plates, said port being adapted to permit air to be freely drawn into the framework. The entrance of sand or dirt into the said ports is prevented by means of shields 29 which are secured to the end plates above said ports and extend downwardly, covering the ports. On the interior, the end plates 11 are provided with flexible flap valves 30, preferably composed of leather or other suitable material, said valves being so arranged that as the pattern table is moved upwardly, air is drawn freely into the framework, and as the table is moved downwardly, the flap valves are closed so that the air entrapped within the framework is expelled between the edges of the pattern table and the side walls 8. The air thus expelled carries along with it any sand or dirt which may have been deposited at the edges of the table. As an additional safeguard to prevent the ingress of sand within the framework, I provide a lip 31 on the inside of the frame 7 beneath the edges of the pattern table.

Referring now to the means for lubricating the operating mechanism, it will be noted that the rock shafts 15 and 16 are hollow, the central opening being closed at the ends by means of the removable plugs 32. The bearings of the rock shafts in the bearing block 18 at substantially the central portion of the machine are lubricated by means of the small ports 33 which open from the chamber within the hollow rock shafts, as will clearly appear on inspection of Fig. 1 and Fig. 2, and the bearings of the rock shafts in the sides of the frame 7 are lubricated by similar ports 34. Oil is carried to the bearings for the inner ends of the links 14 by means of the ports 35 in the rock shafts, and the ducts 36 in the segmental

gears. It will thus be apparent that by removing the plugs 32, the chambers within the rock shafts may be filled with oil and that such oil will lubricate the bearings for the rock shafts as well as the bearings for the links. This method of lubrication is advantageous in that the oil can be supplied from the exterior of the apparatus. The articulated ends of the toggles and links are lubricated by means of the grease cups 37 which are threaded into the toggle pins 38. The toggle pins 38 are provided with a central cavity 39, and external grooves 40 and a port 41 leading from the cavity to the grooves. By turning the grease cups, the lubricant will be forced into the cavity 39 and out into the grooves 40 to lubricate the toggle joints. Access is had to the grease cups by means of the hand holes 42 provided in the sides of the frames 7.

The apparatus described is primarily adapted for use in connection with roll ramming apparatus wherein the sand in the flask is rammed by a roll which is passed back and forth over the flask. In operation, the toggles are actuated to raise the table to the position illustrated in Fig. 2, which movement brings the pattern table together with the pattern it carries into position beneath the lower face of the flask, after which the flask is filled with sand and the ramming of the mold completed. The toggles are then actuated to lower the table and draw the pattern from the mold, after which the flask is removed. It has been found in practice that the weight of the ramming roll has a tendency to cause the pattern table to spring between the points of support. In order to overcome this difficulty, and at the same time to use a pattern table of the lightest possible weight, I provide a mechanism adapted to support the pattern table at substantially the central portion thereof, said mechanism being actuated by the means for raising and lowering the table.

Referring now more particularly to Fig. 2, it will be seen that I have provided a number of brace arms 43 which are keyed to the rock shafts 15 and 16, preferably two in number to a shaft, and mounted adjacent the ends thereof. Mounted in the ends of the brace arms are set screws 44 (see Figs. 2 and 5), said set screws being adapted to come into engagement with the lower faces of the brackets 45 secured to the bottoms of the longitudinal strengthening ribs 46 formed on the pattern table 10. The arms 43 are so arranged that they swing into position beneath the brackets 45 when the toggles are in raised position, as will be seen in Fig. 2. By this arrangement, the pattern table 10 is supported at the center, while at the same time the set screws 44 will readily disengage from the brackets 45 when

the rock shafts are rotated to lower the pattern table. Adjustment is accomplished by regulation of the set screws 44.

What I claim is:

5. 1. A sand molding apparatus comprising in combination a movable pattern support, a pair of toggle members for raising and lowering the support, a pair of intermeshing gears, a pivoted link connecting a gear to each toggle member, and means for rotating one of the gears so as to actuate both toggle members.

10 2. A sand molding apparatus comprising in combination a frame, a movable pattern support mounted therein, a pair of toggle members for raising and lowering the support, a pair of intermeshing gears mounted in the frame and intermediate the toggle members, a pivoted link connecting one gear to a toggle member, a pivoted link connecting the other gear to a toggle member, and means for rotating one of the gears.

15 3. A sand molding apparatus comprising in combination a frame, a movable pattern support mounted therein, a pair of toggle members for raising and lowering the support, a pair of intermeshing gears mounted in the frame and intermediate the toggle members, a link connecting one gear to a toggle member, a link connecting the other gear to a toggle member, and means for rotating one of the gears, said links being connected to the gears on sides opposite the intermeshing sides of the gears.

20 4. A sand molding apparatus comprising in combination a frame, a pattern support movably mounted in said frame, a pair of toggles arranged adjacent opposite ends of the support, a pair of rock shafts mounted in the frame intermediate the toggles, a gear on each shaft, said gears intermeshing with one another, a link connecting one gear with a toggle, a link connecting the other gear with the other toggle and means for rotating one of the rock shafts.

25 5. A sand molding apparatus comprising the combination of a movable pattern table, mechanism for raising and lowering the table, and means automatically moved to operative position to support the table when the said mechanism is actuated to raise the table to operative position.

30 6. A sand molding apparatus comprising in combination a movable pattern support, mechanism for raising and lowering the support, and supporting means independent of said mechanism moved into operative position supporting the table when the pattern support is raised to upper position by said mechanism.

35 7. A sand molding apparatus comprising in combination a movable pattern support, means adjacent the extremities of the support for raising and lowering the support,

and means intermediate said raising and lowering means automatically moved to operative position supporting the table when the table is raised to upper position.

40 8. A sand molding apparatus comprising in combination a movable pattern support, a toggle adjacent each end of the support for raising and lowering it, power means for actuating the toggles, and supporting means intermediate the toggles adapted to support the pattern support, said means being moved to supporting position by the power means when the pattern support is raised.

45 9. A sand molding apparatus comprising in combination a movable pattern support, a toggle adjacent each end of the support for raising and lowering it, a rotary shaft, a connection between the shaft and the toggles, and a brace member mounted on said shaft and adapted to be moved to operative position supporting the pattern support when the shaft is rotated to raise the support.

50 10. A sand molding apparatus comprising in combination a closed frame, a pattern supporting table movably mounted in said frame, mechanism mounted within the frame for raising and lowering the table, said frame being provided with a port, and a valvular device controlling said port, said device permitting air to flow into the frame when the table is being raised and closing when the table is being lowered.

55 11. A sand molding apparatus comprising in combination a frame, a movable pattern table mounted in the frame, said frame and table constituting a closed box, mechanism within said box for raising and lowering the table, the said frame having a port adapted to permit air to flow into the box, 105 and a valvular device controlling said port and adapted to close said port when the table is being lowered.

60 12. A sand molding apparatus comprising in combination a frame open at the top, a pattern supporting table slidably mounted in said frame and closing the top thereof, means within the frame for raising and lowering the table, a plate carried on the table and overlapping a side of the frame, said plate being provided with an opening, and a flap valve controlling said opening and adapted to permit air to flow through said opening into the frame when the table is being raised and closing said opening when the table is being lowered.

65 13. A sand molding apparatus comprising in combination a closed frame, a pattern supporting table movably mounted in said frame, said frame and table constituting in effect a closed box, mechanism within the frame for raising and lowering the table, and valvular means admitting air within the frame when the table is being 130

raised and closing when the table is being lowered.

14. A sand molding apparatus comprising in combination a frame open at the top, 5 a movable pattern supporting table mounted in the frame for vertical movement and constituting with the frame a closed box, means for raising and lowering the table, and valvular means whereby air is admitted into the frame below the table when 10

the latter is being raised and the air cut off when the table is being moved downward.

In testimony whereof I have hereunto signed my name in the presence of the two subscribed witnesses.

HARRY P. MACDONALD.
